United States Patent Office

Des. 197,612
Patented Mar. 3, 1964

197,612

DESK

Albert E. Rice and Ford A. Rice, both of 945 Leader Bldg., Cleveland, Ohio

Filed Mar. 12, 1962, Ser. No. 69,230

Term of patent 14 years

(Cl. D33—7)

Fig. 1

Fig. 2

Fig. 3

FIG. 1 is a perspective view of the desk, embodying the novel design;

FIG. 2 is a back perspective view, and

FIG. 3 is a side elevational view thereof.

The side not shown is the same as FIG. 3.

We claim:

The ornamental design for a desk, as shown and described.
